UNITED STATES PATENT OFFICE

ERNEST KOELLA, OF ROCKFORD, TENNESSEE, ASSIGNOR TO ROCKFORD MANUFACTURING COMPANY, OF ROCKFORD, TENNESSEE, A CORPORATION OF TENNESSEE

TUFTING ROVING

Application filed June 17, 1930. Serial No. 461,776.

This invention relates to rope-form rovings suitable to be cut transversely into pieces to form tufts for tying bed mattresses and similar structures. Such tufts are to be adapted to constitute a key or button to be held by the thread which extends transversely through the mattress in one direction and back in the reverse direction, whereby a loop is formed by the thread, the tuft lying in that loop and against the mattress.

It is essential that the tuft be soft and that it will, after being attached to the mattress, be fluffy and spread so as to fill the dent or depression formed in the mattress cover by the strain of the tying thread which, as above stated, extends through the mattress. Cotton, being soft and elastic, is a material well suited to the making of such tufts. When such a tuft is placed into the loop of the thread which ties the mattress, and the tuft is drawn against the mattress by the tying thread, the tuft is folded over the thread whereby the ends of the tuft spread and form a soft fluffy surface even with or somewhat above the general plane of the mattress cover. No material lacking this softness and elasticity is suitable for making this roving. Indeed, cotton is now largely in use for making such tufts.

The rope-form roving must be so constituted that sections cut transversely from the body will constitute tufts having the qualities above indicated.

Furthermore, provision must be made for rapidly at intervals binding and cutting the body or rope into sections of uniform length. For that purpose, machines are used, the rope-form body being made to pass through a relatively restricted passage in the machine. These machines include means for binding the roving rope transversely at longitudinal intervals before the rope is cut, the cuts being made approximately midway between the bindings, whereby the bindings are placed midway between the ends of the tuft, as is desirable.

In order that the tufts may be of uniform length and the bindings be placed midway between the ends of the tufts, the feeding of the roving rope must proceed with substan-

tial uniformity of speed. That calls for certain qualities or characteristics in the roving rope, as will be explained further on, the absence of those qualities or characteristics rendering the roving rope impractical for treatment in the binding and cutting machine.

The necessary qualities or characteristics of the roving rope are such uniformity in diameter and density as will facilitate such uniform engagement of the rope in its passage through the machine as will cause the presentation of equal lengths of the rope to the binding mechanism and the cutting mechanism of the machine.

In addition to density and uniformity of thickness, the rope must have a degree of longitudinal tensile strength to resist stretching and adapt the rope to be drawn or moved through the machine with uniform speed. Indeed such tensile strength is an aid in producing and maintaining uniform diameter and density. Stretching any rope tends to reduce the diameter of any part that is stretched.

But while the rope is given this density and uniformity of thickness and tensile strength, it must be composed of soft elastic cotton adapting the tufts to expand and present soft and fluffy spread ends when the tufts are applied to the mattress.

These practical and necessary characteristics of the rope relative to the forming of the tufts by the aid of the machine and relative to the finished tufts when applied to the mattress, are to be kept in mind while comparing my invention with analogous rope-form structures disclosed by the prior art.

As examples of the prior art, I cite United States patents as follows: No. 1,163,763, G. A. Lowry, Dec. 14, 1915, "method of making palmetto or palm fiber twine"; No. 1,175,303, L. S. and M. Samuel, Mar. 14, 1916, "strip for weaving and like purposes"; No. 1,184,912, J. D. Armitage, May 30, 1916, "thread or cord and method of preparing the same"; No. Re. 16,101, H. V. Whitlock, June 23, 1925, "rope structure"; No. 1,563,307, L. W. Frank, Nov. 24, 1925,

"tufting wicking or roving yarn"; No. 1,732,593, P. D. Cannon, Oct. 22, 1929, "production of composite yarns and yarn of said character"; and No. 1,738,098, J. C. Coram, Dec. 3, 1929, "apparatus for making textile strands".

According to the Lowry patent, palmetto leaves are shredded and the long fibers are laid side-by-side to make a thin cylindrical body, and that body is twisted and surrounded by a spiral wrapping. The finished product is a hard twine.

The Armitage patent is for a twine or cord to be used in weaving, and it consists of a group of parallel strands surrounded by a single spiral retaining strand of material which is soluble. This twine needs characteristics adapting it to be put into a shuttle and be by the shuttle carried through weaving operation.

The Samuel patent discloses a strip to be used for making portières, rugs, and the like, the strip or strand being strong enough to withstand beating and also withstand the tensional strain which comes from the action of the shuttle during the weaving operation. In each of the three forms shown by the drawing, there is an element consisting of material intended to impart longitudinal strength and hardness.

The Whitlock patent is for a rope built for tensile strength. Every step in the building of the rope looks toward providing tensile strength and durability during continued use involving applying tensional strain. In that rope, density or hardness is also a feature. This rope has no outer spiral thread serving as a binder.

The Frank patent shows a number of roves or strands laid straight and parallel with respect to the axis of the entire structure. Around this bundle of parallel strands is wound a spiral yarn, the convolutions being far apart. The specification mentions that by leaving all the body strands parallel to each other instead of twisting them, ill effect from twisting the entire body of strands is avoided, the exterior strands in such a twisted body of strands being of greater length than the interior strands, and there being then a difference in "back twist". As will be described further on, in my improved structure there is only one layer of spiral strands. Therefore the twisted strands are all of the same length, and if there is tendency to "back-twist", that tendency is uniform throughout the structure.

The structure of the Cannon patent includes asbestos fiber and enough cotton fiber to hold the asbestos fiber. The fibers are placed lengthwise and parallel to each other to form the body. Then "threads or wires" are wound spirally around the body. Then the entire body is twisted in the direction

of the spiral of the thread or wire, whereby the thread or wire is drawn with greater force against the body of fibers.

The Coram patent describes a strand composed mainly of fragments of woven or knitted or felted fabrics, the finished cord being intended especially for making carpets, rugs, or similar heavy fabrics.

Not one of these patents discloses a rope-form structure formed according to my method and having the characteristics herein described concerning my structure. And not one of the structures of this group of patents is adapted to be cut into sections forming mattress tufts having the qualities herein described.

In considering the nature of my improved roving rope, it is to be kept in mind that its chief use is for the production of such tufts as have been above described. In that view, this roving may be regarded as not in itself useful, as not having function. The roving may be regarded as a distinct article of manufacture. It is adapted to pass in trade from a manufacturer of roving to the user of tufts, the latter binding and cutting the roving to form tufts. But the manufacturer of the roving may also bind and cut the roving to form tufts and sell the tufts to users.

This rope roving may also be used as wicking and for similar purposes; but such use is to be regarded as limited and subordinate to the making of tufts for use in the manufacturing of bed mattresses and similar structures.

In the accompanying drawings,

Fig. 1 is a side view of a piece of tufting roving embodying my invention;

Fig. 2 is a perspective of four strands adapted to form the longitudinal core of the structure;

Fig. 3 is a transverse section on the line, 3—3, of Fig. 1, the plane of that section being perpendicular to the axis of the structure;

Fig. 4 is an oblique section on the line, 4—4, of Fig. 1;

Fig. 5 is a side view of a finished tuft;

Fig. 6 is a detail section showing a tuft applied to a mattress;

Fig. 7 is a section on the line, 7—7, of Fig. 6, looking toward the right;

Fig. 8 is a plan showing the tuft of Figs. 6 and 7.

Referring to the drawings, the elements in my completed roving are: (1) several strands, A, of soft cotton fiber lying parallel to each other and in close contact and forming a core; (2) soft cotton spiral or yarns or fine rovings, B, lying parallel to and against each other and against the core, in the form of a single tubular layer completely surrounding the core; and (3) a thin relatively firm thread, C, preferably of cot-

ton, extending spirally around the body formed by the core strands, A, and the spiral soft cotton strands, B, the thread being wound spirally in the direction opposite the winding of the spiral strands, B, and the thread being under sufficient tension to be drawn or pressed into the body formed by the core strands and the spiral strands, whereby the thread is somewhat embedded in said body.

Thus the general surface of the finished structure is of soft cotton, the thread lying inward toward the axis or core of the structure. But it is to be noted that the thread need not be hard. It may be only strong enough to function until the adjacent part of the rope has been bound and cut.

The spirals of the thread, C, are near enough to each other to condense the structure. This action is facilitated by winding the thread transversely to the course of winding of the spiral cotton strands, as above stated. This makes the structure compact and of sufficiently stable form to facilitate feeding the structure through a relatively restricted passage formed in a machine which operates to bind the roving at equal longitudinal intervals and cut the roving between those intervals, the pieces thus cut from the roving forming tufts. In the drawings, the bindings are designated by the letter, D.

Such feeding of the roving must proceed with substantial uniformity of speed, in order that the pieces or sections cut from the roving structure will be of equal length, and in order that the binding, D, or other securing means may be midway between the ends of the tuft, in order that the ends of the folded tuft will be even.

As above stated, the finished tuft, when applied to the mattress, E, by means of the tying thread, F, must be soft and fluffy and must have its ends spread to form a surface substantially even with the general surrounding surface of the mattress. This calls for making the roving to the largest degree of soft elastic cotton. My improved roving consists entirely of such cotton, including, if desired, the thin outer thread, C. In the finished or separated tuft, the short piece of that thread will be embedded in the soft cotton mass which constitutes the body of the tuft, only the ends of the thread coming to the surface of the tuft. If that thread is composed of cotton, spun closely, its loose ends in the finished tuft are adapted to unwind and become parts of the fluffy surface of the applied tuft.

It is also to be noted that, by applying the core and the spiral parallel strands to each other and applying the thread spirally around the body of spiral strands in the opposite direction and under tension, in the manner described, the roving structure is

made sufficiently firm to prevent flattening of the structure and to prevent slipping of the thread coils lengthwise of the structure. This behavior of the structure during movement through the machine is important. It facilitates uniform presentation of the roving to the binding mechanism and to the cutting mechanism, whereby the finished tufts are uniform.

I claim as my invention.

1. In a tufting roving, the combination of a longitudinal soft core, a single layer of spiral soft cotton strands surrounding and bearing on the core and lying parallel to and against each other, and a thread wound spirally around the body formed by the core and the spiral strands, the spirals of the thread being spaced from each other and lying in the direction opposed to the direction of the spiral strands.

2. In a tufting roving, the combination of a group of parallel longitudinal soft cotton core strands, a single layer of spiral soft cotton strands surrounding and bearing on the core strands and lying parallel to and against each other, and a thread wound spirally around the body formed by the core strands and the spiral strands, the spirals of the thread being spaced from each other and lying in the direction opposed to the direction of the spiral strands.

3. In a tufting roving, the combination of a longitudinal soft core, a single layer of spiral soft cotton strands surrounding and bearing on the core and lying parallel to and against each other, and a thread wound spirally around the body formed by the core and the spiral strands, the spirals of the thread being spaced from each other and lying in the direction opposed to the direction of the spiral strands and the thread being under tension whereby it is partially embedded in the spiral strands and the spiral strands are pressed toward and against the core.

4. In a tufting roving, the combination of a group of parallel longitudinal soft cotton core strands, a single layer of spiral soft cotton strands surrounding and bearing on the core strands and lying parallel to and against each other, and a thread wound spirally around the body formed by the core strands and the spiral strands, the spirals of the thread being spaced from each other and lying in the direction opposed to the direction of the spiral strands and the thread being under tension whereby it is partially embedded in the spiral strands and the spiral strands are pressed toward and against the core strands.

5. In a tufting roving, the combination of a longitudinal soft core, a single layer of spiral soft cotton strands surrounding and bearing on the core and lying parallel to and against each other, and a thread wound

spirally around the body formed by the core and the spiral strands, the spirals of the thread being spaced from each other and lying in the direction opposed to the direction of the spiral strands and the spiral strands being under moderate tension and the spiral thread being under more tension.

6. In a tufting roving, the combination of a longitudinal soft core, a single layer of 10 spiral soft cotton strands surrounding and bearing on the core and lying parallel to and against each other, and a cotton thread wound spirally around the body formed by the core and the spiral strands, the spirals of the thread being spaced from each other and lying in the direction opposed to the direction of the spiral strands.

7. In a tufting roving, the combination of a group of parallel longitudinal soft 20 cotton core strands, a single layer of spiral soft cotton strands surrounding and bearing on the core strands and lying parallel to and against each other, and a cotton thread wound spirally around the body formed by the core strands and the spiral strands, the spirals of the thread being spaced from each other and lying in the direction opposed to the direction of the spiral strands.

In testimony whereof I have signed my 30 name, this ninth day of June, in the year one thousand nine hundred and thirty.

ERNEST KOELLA.
